UNITED STATES PATENT OFFICE.

DAVID KUHMARKER, OF NEW YORK, N. Y.

WRAPPING-PAPER PAD.

1,153,503.

Specification of Letters Patent. Patented Sept. 14, 1915.

Application filed December 26, 1914. Serial No. 879,048.

To all whom it may concern:

Be it known that I, DAVID KUHMARKER, a subject of the Emperor of Austria-Hungary, residing in the city of New York, 5 Manhattan borough, county and State of New York, have invented certain new and useful Improvements in Wrapping-Paper Pads, of which the following is a full, clear, and exact description.

10 This invention relates to an improvement in pads, the object being to provide a pad consisting of outer covers between which are located sheets of wax or wrapping paper. My improved pad is composed of the 15 said outer covers, one of which is of the special construction hereinafter described, and a plurality of sheets of wax-paper to be used for wrapping sandwiches, lunches, etc.

16 A further feature of improvement consists 20 in providing one of the covers with an opening through which the paper can be seen, the said opening being spanned by a sheet of transparent celluloid, or other flexible transparent substance, to keep out dust, etc.

25 A still further feature of my improvement consists in providing one of the covers with a paper-cutter so that less than a full sheet can be cut and extracted from the pad.

30 I will now proceed to describe my invention in detail, the novel features of which I will point out in the appended claims, reference being had to the accompanying drawing, forming part hereof, wherein—

35 Figure 1 is a perspective view of my improvement; Fig. 2 is an enlarged sectional detail view, the section being taken on a line 2—2 in Fig. 1; Fig. 3 is a similar view illustrating the top cover as lifted in order that a sheet can be cut off intermediate the 40 ends thereof; and Fig. 4 is an enlarged sectional view, the section being taken on a line 4—4 in Fig. 1, the sheets of paper and opening 12 being omitted.

45 As herein illustrated, my improvement consists of a top cover 1 and a lower cover 2, which may be connected at one end by a strip 3 (Fig. 4) this however being optional.

46 As shown in Fig. 1 the top cover 1 is provided with an opening 5 through which the 50 sheets of paper 6 can be seen, the said opening being spanned or covered by a transparent film 7 (Fig. 4). Intermediate the ends of the cover 1, I place a cutter 8, by which means a part or section of one or more of

the sheets of paper constituting the pad can 55 be cut off. The sheets of paper 6 are secured together and to the covers, at one end thereof, in any desirable manner, such as by stitching or by fasteners 9. The covers, especially the top cover 1, are made preferably out of some flexible material so that the top cover can be bent upwardly, as shown in Fig. 3, in order that one or more sheets can be grasped and raised at one end thereof, and pulled upwardly against the edge 10 60 of the cutter 8, whereby the said sheet or sheets will be severed at the line of contact with the cutter. The cutter 8 will be held against the pile of sheets 6 by one hand during the cutting operation. As will be seen 65 in Fig. 4 the cutter 8 is secured along one edge 11, to the cover 1; hence the said cover can be bent away from the cutting edge of the cutter to facilitate the cutting of a sheet or sheets. The pad is provided with an 70 opening 12 at one end thereof by which means the pad can be hung up. The cutter is preferably made out of thin metal or strong cardboard and can be secured to the cover 1 in any desirable manner, such as by 75 paper fasteners, rivets, glue, etc.

One of the advantageous features of the sight-opening or window 5 in the top-cover 1 is that, although the pad be fully covered, a trademark, watermark or other indication 85 on the sheets of paper 6 will always be visible, if placed at a point subjacent the said opening, without lifting up or removing the cover.

Having now described my invention, what 90 I claim and desire to secure by Letters Patent is:

1. A pad of wrapping paper, comprising a plurality of sheets of paper, a flexible cover for the pad, and a cutter on the under 95 surface of said cover, the said cutter being secured, along one of its edges only, to the cover, that portion of the cover between the point of securement to the cutter and the free edge of the cover being free to be moved 100 away from the cutting edge of the cutter, substantially as and for the purpose described.

2. A pad of wrapping paper, comprising a plurality of sheets of paper, a cover for 105 said pad, and a cutter carried by said cover intermediate the ends thereof and located on the under surface of said cover, the cutter

being secured, along one of its edges only, to said cover, whereby that portion of said cover between the point of securement to the cutter and the free edge of the cover can be 5 rolled backwardly to expose the sheets of the pad without raising the cutter from the pad.

Signed at New York city, N. Y., this 23d day of December, 1914.

DAVID KUHMARKER.
